H. W. PARTON.
CARPET.

No. 20,599.

Patented Mar. 24, 1891.

UNITED STATES PATENT OFFICE.

HENRY W. PARTON, OF YONKERS, NEW YORK, ASSIGNOR TO THE ALEX. SMITH & SONS CARPET COMPANY, OF SAME PLACE.

DESIGN FOR A CARPET.

SPECIFICATION forming part of Design No. 20,599, dated March 24, 1891.

Application filed February 7, 1891. Serial No. 380,666. Term of patent 3½ years.

To all whom it may concern:

Be it known that I, HENRY W. PARTON, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

My design consists of the body A and border B. The body A consists of a large panel containing a group of conventionalized flower forms resembling poppies and of leaf forms on a shaded ground surrounded by darker ground of conventionalized flower and leaf forms. The border B consists of a panel containing a group of conventionalized flower forms resembling poppies and of leaf forms on a shaded ground surrounded by darker ground of conventionalized flower and leaf forms running into an irregular marginal decoration. 25

What I claim as new, and desire to secure by Letters Patent, is—

1. The design for carpets, consisting of the body A, substantially as shown. 30
2. The design for carpets, consisting of the border B, substantially as shown.
3. The design for carpets, consisting of the body A and the border B, substantially as shown. 35
